UNITED STATES PATENT OFFICE.

CYRUS BATES, OF HARDIN, IOWA.

IMPROVEMENT IN GRAIN-SEPARATORS.

Specification forming part of Letters Patent No. 40,670, dated November 24, 1863.

To all whom it may concern:

Be it known that I, CYRUS BATES, of Hardin, in the county of Clayton and State of Iowa, have invented a new and Improved Grain-Separator; and I do hereby declare that the following is a full, clear, and exact description of the same, reference being had to the accompanying drawings, making a part of this specification, in which—

Figure 1 is a side sectional view of my invention, taken in the line $x x$, Fig. 2. Fig. 2, a plan or top view of the same.

Similar letters of reference indicate corresponding parts in the two figures.

The object of this invention is to obtain a grain-separator which will effectually separate the best wheat from the inferior portion together with the chaff, chess, and other foreign substances, the invention admitting of being so regulated or adjusted that the separation of the prime from the inferior wheat may be made as close as desired—that is to say, so as to separate No. 1 wheat only from the second quality, or to take in more or less of the latter, as may be required.

To this end the invention consists in the employment or use of a sliding or adjustable screen having a board attached and placed underneath the series of screens contained in an ordinary shoe, and using in connection with the screen and board aforesaid a screen placed underneath the former and provided with a trap, the latter having a spout underneath it, and all arranged in such a manner that the inferior wheat, together with chess, oats, and other foreign substances, will be conducted by the board of the adjustable screen to the trap of the screen below, and will fall through said trap into any proper receptacle, while the sound wheat will pass directly through the adjustable screen and the screen below and be discharged at the front end of the machine.

To enable those skilled in the art to fully understand and construct my invention, I will proceed to describe it.

A represents the box or case of the separator, B the fan, and C a shoe containing a series of screens, *a*. These parts may all be constructed and arranged in the usual way, and therefore do not require a minute description.

In the lower part of the shoe C there is placed a short screen, D, which has a board or

plate, E, attached to its lower or depressed end. This screen D and its board or plate E are fitted between grooves *b* in the sides of the shoe, so as to render it capable of being adjusted farther forward or backward in the shoe, as may be required. In the box or case A, underneath the shoe C, there is an inclined screen, F, the latter being inclined in a reverse direction to the screens *a* and D in the shoe C, as shown clearly in Fig. 1. At the upper or elevated end of the screen F there is a board or plate, *c*, which extends the whole width of screen F, said board or plate containing a trap-door, G, the latter extending the whole width of the board or plate *c*. Underneath the trap-door G there is a spout, H, and I is a box placed underneath said spout. J is a hopper placed on the upper part of the box or case A.

The operation is as follows: The wheat passes from the hopper J down into the shoe C and through the screens *a a*, and is subjected to a blast from the fan B, which expels all the light, foreign impurities from the shoe C. The sound wheat, owing to its superior gravity, passes directly through the screens *a*, and also through the short screen D, and falls upon the screen F, from the lower end of which it is discharged. The inferior wheat, chess, oats, &c., will, owing to their lightness, be impelled forward under the action of the blast from the fan so that they will fall upon the board or plate E, and will fall from thence upon the board or plate *c* of the screen F, and will pass through the trap-door G into the spout H, and from thence into the receptacle or box I. In case it is desired to separate only the very best quality of wheat from the inferior portion, the short screen D is adjusted considerably back in the shoe C, so that only the prime wheat will fall upon it, and if a very nice or close separation is not required, the screen D is shoved sufficiently far forward in the shoe C so that more or less of the second quality of wheat may fall upon screen D. Thus it will be seen that by this simple arrangement the prime wheat may be separated from the inferior portion and the separation made as close or exact as required, and at any time the machine may be used in the ordinary way without making such separation by simply closing the trap-door G.

The shoe C has the usual lateral vibrating movement, and the screen F is vibrated longitudinally.

Having thus described my invention, what I claim as new, and desire to secure by Letters Patent, is—

The adjustable screen D, with the board or plate E attached and placed in the shoe C,

in combination with the screen F, provided with the trap-door G, all arranged to operate substantially as and for the purpose herein set forth.

CYRUS BATES.
